UNITED STATES PATENT OFFICE

HERBERT THORNE, OF BOSTON, MASSACHUSETTS, ASSIGNOR TO MODERN CURTAIN CO., INC., OF BOSTON, MASSACHUSETTS, A CORPORATION OF MASSACHUSETTS

CURTAIN

Application filed June 25, 1932. Serial No. 619,271.

This invention pertains to window curtains, draperies, or the like and more particularly to an improved border construction for curtains or the like.

5 In the manufacture of window curtains it is customary to provide a border, for example, a ruffle, at the edge of the body material, and to set off the border from the body fabric, for instance, by the use of parallel 10 sewed seams, the material between the seams being gathered or tucked to produce a distinctive band, and at the same time to conceal the actual junction of the border and body of the curtain, particularly when the 15 border and body are separate pieces of material. Most of the materials employed for curtains are thin, sheer, or gauzy, and the material is frequently ornamented with thickened spots as in marquisettes, and I find 20 that when such materials, particularly those having spots, are gathered at the junction of the body fabric and the border, as above described, an irregular, non-uniform, and unpleasing appearance frequently results, while 25 the raw edges of the border and the body fabric are not always sufficiently concealed.

In accordance with the present invention, and with the principal object of avoiding the above-noted defects in prior construction, 30 I cover the junction between the border and body fabric with a narrow band, for example, tape, ribbon, or a narrow strip of any suitable material separate from the body fabric and border, and I preferably secure this 35 band in place by the sewed seams commonly provided at the junction of the body and border. Preferably this band is tucked, together with the border fabric, whereby to 40 impart the desired ruffled effect to the border and at the same time to lay the covering band in regular tucks or pleats, thereby increasing its effective thickness as a joint covering or concealing means, as well as its opacity, 45 thereby setting off the border from the body material in a very effective manner. If desired, the covering band may be of a contrasting color, although this is not essential. Conveniently this band may be provided by 50 feeding a narrow continuous strip of suitable material from a source of supply, so that

it is delivered at the proper point to receive the needles which form the aforementioned parallel seams, and, if the edges of this strip are raw, they are turned in before sewing, for example by passing the strip through a 55 suitable hemmer. Preferably an edge of the body fabric and an edge of the border material are also turned to form hems, the several hemming operations and the tucking being carried out in the proper order to produce the desired structure. Preferably the tucker comprises a pair of blades (or a single blade having independently acting portions) adapted to act upon the thick mass of material including the band, border, and 60 body fabric, and upon the relatively thin material of the border respectively. If desired, the border-engaging blade or blade portion may be omitted and the tucking operation 65 confined to the band and the material directly beneath it.

In the accompanying drawing wherein certain desirable embodiments of the invention are shown by way of example:

Fig. 1 is a fragmentary plan view, to small 75 scale, illustrating the corner of a curtain formed of dotted material and embodying the present invention;

Fig. 2 is a section to large scale substantially on the line 2—2 of Fig. 1;

Fig. 3 is a section to large scale substantially on the line 3—3 of Fig. 1;

Fig. 4 is a fragmentary more or less diagrammatic elevation showing a portion of a sewing machine and attachments appropriate for producing the curtain herein described;

Fig. 5 is a bottom plan view of a hemmer device useful in folding the band;

Fig. 6 is a section substantially on the line 90 6—6 of Fig. 5 showing the hemmer right side up;

Fig. 7 is a fragmentary transverse section of a second hemmer device useful in hemming the border material and in assembling 95 the latter with the band;

Fig. 8 is a fragmentary plan view of the tucking device showing the two-part blade;

Fig. 9 is a fragmentary plan view showing a modified curtain construction; and 100

Fig. 10 is a bottom view of the curtain shown in Fig. 9.

- Referring to the drawing, the numeral 1 designates the body portion of the curtain 5 and the numeral 2 indicates the border, shown in Fig. 1 as a ruffle. The edge of the body portion 1 is folded upon itself, as shown at 3 (Fig. 3), to form a two-ply hem structure, while the border material 2 preferably 10 is folded at the points 4 and 5, respectively (Fig. 3), to form a three-ply hem structure, the hem structure of the border being superposed upon the hem structure of the body portion.
- 15 Above the folded hem of the border I arrange a band 6 which may consist of ribbon, tape, or a narrow strip of any other suitable material, and if this band material has raw edges, it is preferably folded at 7 and 8 (Fig. 20 3) to form marginal hems which overlie the hem structures of the body material and border. The several parts are secured by substantially parallel sewed seams 9 and 10. The band 6 and preferably the underlying 25 hem portion of the border material are formed into regular tucks or pleats 12, the tucks being held in position by the seams 9 and 10. Thus if the material of the body 1 and/or of the border 2 is provided with or 30 ornamental dots 11 constituting thickened areas of the fabric, such dots are wholly concealed by the strip 6, which serves to cover the junction of the body and border fabric and which is adapted to be tucked evenly and regularly, 35 whereas dotted material, when subjected to the tucking operation, forms irregularities producing an unpleasing and unfinished appearance. By imparting a tucked form to the strip 6, its effective thickness and opacity are increased so that it conceals the junction of the border and body materials, at the 40 same time forming an opaque area which sets off the border from the body. If desired, this band 6 may be of material of a color 45 which contrasts with that of the body and border, although this is not essential.

In producing this improved construction I may employ apparatus such as illustrated, for example, in Figs. 4 to 8 inclusive. Referring to these figures, the numeral 13 designates a portion of the head of a sewing machine of any usual type, such head guiding the needle bar 14, which is adapted to carry two or more needles, and also supporting 50 the presser foot 15 which is adapted to hold the work down against the work-rest 16. The head 13 also supports bracket 17 adapted to carry a roll 18 of the material 6^x adapted to form the band 6, while the head 13 also carries a bracket 20 for supporting the hemming devices. A rocker arm 21 actuated from some suitable part of the sewing machine operates the tucking devices, herein-after referred to.

55 The strip material 6^x is first led through

a hemmer device 22 preferably supported by a flexible connection 23 secured to the main hemmer 24 carried by the bracket 20. The hemmer 22 comprises an outer shell 25 and an inner resilient tongue 26 and is adapted to fold in the margins of the strip material 6^x at the points 7 and 8, respectively. The folded strip material 6^x is then fed to the hemmer 24 in a transversely curved condition, as shown in Fig. 7, one of its edges, for example, the left-hand edge 7 of the folded strip material, being lower than the other edge. The border material 2 is also fed into this hemmer 24, which first forms the fold at 5 and subsequently the fold at 4. From inspection of Fig. 7, it will be noted that the fold 7 of the strip material 6^x is disposed laterally of the fold 4 during the passage of the material through the hemmer 24.

As the material emerges from the hemmer 24, the folds 7 and 4 of the strip material 6^x and the border portion 2 engage the upstanding guide flange 27 of the tucking mechanism, which crowds the fold 7 to the right and the accurate registry of the folds 7 and 4 as they approach the needles is thus assured. The tucking device preferably comprises a reciprocating blade 28 of resilient material slit longitudinally to provide the two effective blade portions 29 and 30, respectively. The portion 29 acts upon the folded margin of the border material 2 and preferably upon the band material 6^x to form regular uniform tucks in these materials, while the blade portion 30 acts upon the thin single ply of the border material 2 at one side of the band 6. The border material is thus thrown into ruffles by the concomitant action of the blade portions 29 and 30, while the band material 6^x is formed into regular and uniform tucks which enclose portions of the border material, as shown in Fig. 2. Under some circumstances the blade portion 30 may be dispensed with, although this is desirable in securing regularity of the ruffled effect in the border material.

In Figs. 9 and 10 I have illustrated a modified arrangement of the curtain structure in which the body portion 31 and the border portion 32 are overlapped and the junction between them covered by the tucked strip 33, the several parts being held together by the sewed seams 9^a and 10^a. In this arrangement the border material 32 is not ruffled and need not be caught within the tucks of the band material 33. This produces a junction between the parts which is somewhat thinner than that produced by the aforesaid method and leaves a flat unruffled border, although the tucked band 33 effectively conceals the junction between the body and border in the same way as the band 6 in the construction previously described.

Obviously various changes in detail and

in relative arrangement of parts may be made within the scope of the invention.

I claim:

1. A curtain having a body portion and a ruffle each having a multi-ply hem, means uniting the hems of the body portion and ruffle, and a substantially straight band of material superposed upon the junction of the body portion and ruffle, said band being regularly tucked to increase its thickness and opacity.

2. A curtain having a body portion and a border portion, said body portion and border portion having multi-ply hems respectively disposed in superposed relation, a pair of parallel sewed seams uniting said superposed hems of said body and border portions, and a substantially straight covering band concealing the junction of the body and border portions, said band being secured in position by the aforesaid seams and being regularly tucked to increase its thickness and opacity.

3. In a curtain having a body portion and a ruffle, the latter at least being of a fabric ornamented by relatively thick dots; a substantially straight band covering and concealing the junction of the body and ruffle, and spaced sewed seams uniting the body, ruffle and band, said band having its edges folded under and comprising a series of regularly disposed tucks operative to conceal irregularities in thickness in the junction of the border and ruffle occasioned by inclusion

in said junction of dots of the ruffle material.

4. In a curtain having a body portion and a ruffle each formed of fabric ornamented by relatively thick areas; a substantially straight band covering and concealing the junction of the body and ruffle, and a pair of spaced parallel sewed seams uniting the body, ruffle and band, the band comprising tucks operative to conceal the junction of the band and ruffle, the tucks being regularly arranged irrespective of the inclusion of thickened areas of the body and ruffle at their junction.

5. A curtain having a body portion and a border, parallel sewed seams joining the body and border, and a band of material independent of the body and border united thereto by said seams, said band and the underlying portions of the border comprising regularly disposed tucks operative to increase the effective thickness of the material as well as its opacity, whereby to conceal and finish the junction of the body and border.

6. A curtain having a body portion and a ruffle, parallel sewed seams joining the body and ruffle, and a band of material independent of the body and ruffle united thereto by said seams, said band overlying the ruffle and the band and ruffle together being regularly tucked, tucks of the band material enclosing portions of the tucked border material.

Signed by me at Boston, Massachusetts this 24th day of June 1932.

HERBERT THORNE.
